GRAIN CLEANING DEVICE

Emory William Douglass, Douglas, Minn.

Application October 12, 1931, Serial No. 568,465

1 Claim. (Cl. 209—341)

My invention relates to improvements in grain cleaning devices, and it consists in the combinations, constructions, and arrangements herein described and claimed.

An object of my invention is to provide a grain cleaning device which sifts the grain in a manner similar to the hand operated pan sifter.

A further object is to provide a grain cleaning device in which the sieves may be shaken smoothly so that they will not cause the grain disposed therein to jump.

A further object is to provide a grain cleaning device having a construction which will eliminate any tendency to shake the screens jerkily even after prolonged use.

A further object is to provide a grain cleaning device in which the sieves may be readily removed and replaced by other sieves thereby adapting the device for use in cleaning different kinds of grain.

A further object is to provide a grain cleaning device in which the degree of vibrations of the sieves may be changed.

A further object is to provide a grain cleaning device in which only the vibrations extending in definite directions are utilized for vibrating the sieves.

A further object is to cause the motor to gyrate and to so mount the motor in part on the casing as to enable damping the impulses in one direction and resolving them into what are herein called drumhead vibrations, and taking full advantage of the impulses in a direction substantially at right angles and resolving them into reciprocations, the vibrations keeping the meshes of the sieves from filling up and the reciprocations imparting the necessary shaking to the sieves to keep the material moving.

A further object is to provide a spring suspension both for the sieve-casing and the fan motor and to unbalance the motor shaft so as to cause the motor to gyrate and set up vibrations in the casing to shake its sieves.

Other objects and advantages will appear in the following specification, and the novel features of the invention will be particularly pointed out in the appended claim.

My invention is illustrated in the accompanying drawings, forming part of this application, in 50 which

Figure 1 is a side elevation of my device,

Figure 2 is an end elevation of my device,

Figure 3 is a vertical sectional view of my device taken along the line 3—3 of Figure 2, and 55 Figure 4 is an end elevation of my device, a por-

tion thereof being broken away and shown in section.

In carrying out my invention, I provide a supporting structure or frame 1 comprising a plurality of upright members or posts 2, 3, 4, and 5. The upright members 2 to 4, inclusive, have their top ends connected with side bars 6 and end bars 7. The upright members and bars may be secured together in any suitable manner such as by bolts or rivets 8. Stiffening plates 9 may also be connected with the upright members and bars for giving the supporting structure greater rigidity.

Cross-members 10, 11, and 12 are connected with upright members adjacent the lower ends 15 thereof by any suitable means such as rivets 13.

A cross-member or housing supporting bar 14 is positioned between the upright members 2 and 3 and is adapted for being connected therewith in any suitable manner.

A hopper 15 having inclined side portions is carried by the supporting structure and is provided with an opening 16 in the bottom thereof as shown in Figure 3. A movable suspension casing 17 is disposed within the supporting structure and is positioned beneath the hopper 15. The casing 17 comprises a pair of spaced-apart wall portions 18 which may be made of sheet material and have the contour shown in Figure 1. The spaced-apart wall portions 18 are provided with reinforced end portions 19 which are connected together by tie rods 20.

The casing 17 has an end wall 21 which is cut away for providing an air inlet opening 22 and a grain outlet opening 23. The walls 18 are further provided with projecting portions 24 which extend over the cross-member 12.

Each of the wall portions 18 is provided with a flange portion 25 such as an angle bar which may be connected therewith by any suitable means such as rivets 26.

A pair of resilient or spring members 27 is provided for supporting an end of the casing 17. Each of the resilient members 27 has one end connected with a flange portion 25 and the other end connected with one of the cross-members 10, 11, 12 of the supporting frame. In like manner a pair of resilient or spring members 28 is provided for supporting the other end of the casing. Each of the resilient members 28 has one end connected with one of the flange portions 25 and the other end connected with a cross-member of the supporting frame. The spring members 27 and 28 movably support the casing 17.

The upright members 4 and 5 are provided 55

with resilient or spring members 29 which are connected with the side bars 6 and end bars 7 of the supporting frame. The spring members 29 are provided for supporting the side bars 6 and end bars 7 of the supporting frame.

The side bars 6 and end bars 7 are provided with resilient or spring members 30 which are connected with the side bars 6 and end bars 7 of the supporting frame.

with flange members 29 fixedly connected therewith. The flange members 29 are each provided with a rod member 30 having an end connected therewith and slidably extending through an opening in one of the resilient members 28. The other end of the rod is threaded for receiving a threaded member, such as a nut 31. Expansion springs 32 and 33 are mounted on the rod 30. The expansion spring 32 is positioned 10 between the nut 31 and the spring member 28 and the expansion spring 33 is positioned between the spring member 28 and the flange member 29.

A motor housing or wind box 34 is movably 15 supported by spring members 35 which, in turn, are carried by the cross-member 14 of the supporting structure 1. While I have shown the housing as being mounted on coil springs, it will be understood that the housing may be movably 20 mounted in suspension by any suitable means. The housing 34 is of a length substantially equal to the distance between the spaced-apart wall portions 18. The housing is provided with a pair of projecting portions 36 fixedly connected 25 therewith. A pair of actuating arms 37 is provided. Each of the arms 37 has an end connected with one of the projecting portions 36 and the other end connected with one of the spring members 28. The housing 34 is provided 30 with a rounded side 38 and flat top and bottom sides 39 and 40. The interior side 41 of the housing 34 is open and substantially in alignment with the opening 22 of the casing 17 for providing communication between the housing 34 and the casing. The ends 42 of the housing 35 are provided with openings 43 therein. A motor 44 is mounted within the housing 34 and is provided with projecting shaft portions 45.

A member 50 is fixedly mounted on each of 40 the shaft portions 45 and comprises a pair of diametrically opposed arm portions 51 and 52. A fan blade 46, preferably of the paddle type, may be connected with one of the arm portions, such as the arm portion 51. A weight member 45 53 may be adjustably connected with the other arm portion 52 by any suitable means, such as a set screw 54, so that the distance between the weight member and the shaft may be varied.

The weight members are positioned on the 50 same sides of the shaft portions. If so desired, a plurality of fan blades may be connected with each of the shaft portions.

It will be noted by referring to Figure 3 of the drawings that a plurality of inclined screens 55 or sieves 47 are disposed within the casing 17 and extend between the walls 18 thereof. The sieves are positioned one above the other and are held in spaced-apart positions by means of strip members 48 connected with the walls 18. 60 The sieves are slidably disposed between the strip members 48 with which they are in frictional engagement and are thereby held against displacement while the device is in operation.

The wall portions 18 have their lower edges 65 provided with flange portions 49 for supporting a screen or sieve 54 positioned beneath the screens 47 and extending between the wall portions 18. The screen 54 is oppositely inclined with respect to the inclined screens 47 and extends to the 70 ends of the projecting portions 24 of the wall portions 18. It will be noted on referring to Figure 3 that the end of the lowermost screen 47 adjacent the wall 21 is positioned just above the opening 22 from which place it extends downwardly in an inclined plane. It will thus be

seen that the lowermost screen 47 is positioned in the path of a wind current generated by the fan 46 and forced through the opening 22 of the casing 17. The remainder of the screens 47 are substantially parallel to the lowermost screen 47 5 and consequently will also be positioned in the path of the wind current.

The motor 44 is in communication with a source of electricity by means of conductors 51 connected therewith and extending through an 10 opening in the housing 34.

From the foregoing description of the various parts of the device, the operation thereof may be readily understood.

The electric current is first turned on for 15 causing the motor to be put into operation for rotating the shaft 45, thereby causing the fans 46 and the weights 53 to be rotated. The weights 53, being heavier than the fans 46 (Fig. 4) throw the motor shaft 45 out of 20 balance. The reaction upon the motor itself and upon the housing 34 is a substantially circular motion about the normal axis of the motor shaft when stationary. The motor (and it is the motor about which there is chief concern) thus 25 has gyroscopic impulses which are used in agitating the seeds.

But it is not desired to utilize these impulses just as they occur, but rather to control them 30 in such a way that they will act on the sieve-casing 17 chiefly in two directions. At first the gyroscopic impulses will be evident by a slight compressing and expanding action of the springs 35 (Fig. 4). Naturally this action increases as 35 the motor speeds up.

It is easy to see that the springs 35 afford an outlet, so to speak, for a portion of the gyroscopic impulses of the motor which are thereby concentrated on the springs and are resolved into a 40 bouncing motion in the vertical direction. Since the springs are connected with the actuating arms 37 through the housing 34 and the projections 36 (Fig. 4) it follows that said arms will be vibrated at their right ends (Fig. 1) and flexed somewhere near their left ends where 45 they are attached to the members 28.

The vibrations will not be so great at the left, because they have been damped out, but there 50 will be some vibration that will be transmitted to the sieve-casing 17 in the vertical direction, and this has been called a drumhead vibration since it simulates the action of a drumhead upon being struck. This so-called drumhead vibration is particularly useful in keeping the meshes 55 of the sieves from filling up.

Getting back to the gyroscopic impulses of the motor, there will be a very distinct set of vibrations in the direction substantially at right angles to the vertical axis of the springs 35. 60 These vibrations run in the direction of the actuating arms 37, these arms offering an outlet for another portion of the gyroscopic impulses which are thus resolved into horizontal reciprocations and are practically unrestricted.

When considering the vertical set of vibrations the arms 37 flex to a degree while the spring members 27, 28 remain stiff, but when considering the horizontal set of vibrations the actuating arms 37 remain stiff while the spring members 27, 28 flex. Therefore the springs 35, 70 projections 36, arms 37 and spring members 27, 28 constitute an arrangement whereby the gyroscopic impulses of the motor are converted into damped vertical vibrations of the casing 17 and 75

practically undiminished horizontal reciprocations for shaking the casing and the contents of the sieves. It is to be especially noted that this arrangement prevents said impulses from running wild, so to speak, and confines them to the two well defined paths or directions substantially at right angles to each other. The frequency of the vibrations or oscillations of the sieves is determined by the speed of the motor and the length of a vibration or oscillation is determined by the distance that the weight members are removed from the shaft. The grain to be cleaned is first deposited in the hopper 15, from whence it passes through the opening 16 in the bottom thereof and onto the top sieve 47. The opening 16 is of a size to permit the proper flow of grain from the hopper to the sieve 47. The shaking or vibrating of the sieves 47, aided by the windblast from the fans 46, removes both the coarse material and the light material from the grain, in view of the fact that the coarse material cannot go through the sieves 47 and the light material is blown therefrom by the windblast. The grain passes through the sieves 47 and falls on the sieve 50. The mesh of the screen or sieve 50 is such that the grain deposited thereon will not fall therethrough but that any smaller seeds (commonly called screenings) may pass therethrough. The cleaned grain which remains slides along the screen 50 to the end thereof, from which it falls.

The device may also be utilized for cleaning and separating two kinds of grain which have been grown together. In this case the grains are deposited on the screens 47 and are cleaned in the manner hereinbefore described. The seeds fall through the screens 47 and are deposited on the screen 50. The openings in the screen 50 are such that one of the grains may fall therethrough

and the other of the grains will be prevented from falling therethrough. The type of screens 47 and 50 used in the device depend on the kind of grain or grains which it is desired be cleaned or separated. The sieves 47 and 50 may be easily removed and replaced by other sieves, thereby adapting the device for cleaning or separating different kinds of grains. The sieves 47 and 50 may be of any suitable type, of which there are several, and therefore a detailed description of the same is not believed necessary.

While my invention has been shown and described as a grain cleaning or separating device, it will be readily understood that the device may be used in various manners, such as for sifting flour or separating flour and bran. In certain of these connections, it might be found desirable to dispense with the windblast, in which case the fans may be disconnected from the motor shaft. It will also be understood that while I have shown and described my invention according to a certain specific structure, certain modifications may be made in that structure without departing from the spirit or scope of my invention.

I claim:

A grain-cleaning device comprising a frame, a sieve-casing, resilient members attached to the casing and the frame to support the casing for reciprocatory motion, at least one actuating arm attached at one end to one of the resilient members, a spring and means by which the spring is mounted on the frame, a motor housing supported on said spring and having a projecting portion resting on the other end of the actuating arm, and a motor mounted in said casing, said motor having a shaft with means to unbalance it upon rotation thereby to gyrate the motor.

EMORY WILLIAM DOUGLASS.
